(57) **CLAIM**

The ornamental designs for a diffuser, as shown and described.

DESCRIPTION

FIG. 1 is a perspective view of a first embodiment of a diffuser,

FIG. 2 is a front view thereof,

FIG. 3 is a rear view thereof,

FIG. 4 is a left-side view thereof,

FIG. 5 is a right-side view thereof,

FIG. 6 is a top view thereof,

FIG. 7 is a bottom view thereof;

FIG. 8 is a perspective view of a second embodiment of a diffuser,

FIG. 9 is a front view thereof,

FIG. 10 is a rear view thereof,

FIG. 11 is a left-side view thereof,

FIG. 12 is a right-side view thereof,

FIG. 13 is a top view thereof; and,

FIG. 14 is a bottom view thereof.

The broken line showing portion of the diffuser is included for the purpose of illustrating environmental structure and forms no part of the claimed design.
